United States Patent Office

Des. 224,397
Patented July 25, 1972

224,397

TRAILER

Arlen L. Huff, South Bend, Ind., assignor to Sellers
Manufacturing, Inc., Wakarusa, Ind.

Filed Apr. 1, 1971, Ser. No. 130,568

Term of patent 14 years

Int. Cl. D12—10

U.S. Cl. D14—3

Fig. 1

Fig. 2

Fig. 3

FIG. 1 is a perspective view of a trailer embodying the present invention;

FIG. 2 is a rear elevational view of the trailer shown in FIG. 1;

FIG. 3 is a front elevational view of the trailer shown in FIG. 2;

FIG. 4 is a top plan view; and

FIG. 5 is a side elevational view.

The side opposite the side shown in FIG. 1 of the trailer is the same design as the side shown.

I claim:

The ornamental design for a trailer, substantially as shown and described.
